(57) **CLAIM**

The ornamental design for a vacuum cleaner, as shown and described.

DESCRIPTION

FIG. 1 is a front view of a vacuum cleaner showing the claimed design;
FIG. 2 is a rear view thereof;
FIG. 3 is a top view thereof;
FIG. 4 is a bottom view thereof;
FIG. 5 is a left view thereof;
FIG. 6 is a right view thereof;
FIG. 7 is a perspective front, top, right view thereof;
FIG. 8 is a perspective front, top, left view thereof;
FIG. 9 is a perspective rear, top, right view thereof; and
FIG. 10 is a perspective rear, top, left view thereof.
FIG. 11 is a front view of another embodiment of a vacuum cleaner showing the claimed design;
FIG. 12 is a rear view thereof;
FIG. 13 is a top view thereof;
FIG. 14 is a bottom view thereof;
FIG. 15 is a left view thereof;
FIG. 16 is a right view thereof;
FIG. 17 is a perspective front, top, right view thereof;
FIG. 18 is a perspective front, top, left view thereof;
FIG. 19 is a perspective rear, top, right view thereof; and,
FIG. 20 is a perspective rear, top, left view thereof.
The broken lines in the drawings depict portions of the vacuum cleaner that form no part of the claimed design.

1 Claim, 18 Drawing Sheets
